(57) **CLAIM**

The ornamental design for a device for collecting blood samples as shown and described.

DESCRIPTION

FIG. 1 is a rear perspective view of a device for collecting blood samples, according to an embodiment;

FIG. 2 is a top view of the device, according to an embodiment;

FIG. 3 is a bottom view of the device, according to an embodiment;

FIG. 4 is a left side view of the device, according to an embodiment;

FIG. 5 is a right side view of the device, according to an embodiment;

FIG. 6 is a rear view of the device, according to an embodiment;

FIG. 7 is a front view of the device, according to an embodiment; and,

FIG. 8 is a front perspective view of the device, according to an embodiment.

The broken lines illustrate portions of the device for collecting blood samples that form no part of the claimed design.

1 Claim, 7 Drawing Sheets
